US0D1098223S

(12) **United States Design Patent** (10) **Patent No.:** **US D1,098,223 S**
(45) **Date of Patent:** **** Oct. 14, 2025**

(54) **WELDING MACHINE**

(71) Applicant: **TECNA S.P.A.**, Castel San Pietro Terme (IT)

(72) Inventor: **Fabrizio Brintazzoli**, Castel San Pietro Terme (IT)

(73) Assignee: **TECNA S.P.A.**, Castel San Pietro Terme (IT)

(**) Term: **15 Years**

(21) Appl. No.: **29/867,351**

(22) Filed: **Oct. 20, 2022**

(30) **Foreign Application Priority Data**

Apr. 27, 2022 (EM) 009008493-0001
Apr. 27, 2022 (EM) 009008493-0002

(57) **CLAIM**

The ornamental design for a welding machine, as shown and described.

DESCRIPTION

FIG. 1 is a perspective view of a welding machine showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a bottom perspective view thereof;

FIG. 9 is a bottom perspective view thereof; and,

FIG. 10 is a top perspective view thereof.

(Continued)

The broken lines in FIGS. 1-10 represent portions of the welding machine and form no part of the claimed design.

1 Claim, 9 Drawing Sheets
